SHOE-TREATING MACHINE

Fred Ricks and Frank Coleman Choice, Leicester, England, assignors to United Shoe Machinery Corporation, Paterson, N. J., a corporation of New Jersey

Application February 16, 1937, Serial No. 126,010
In Great Britain March 13, 1936

5 Claims. (Cl. 12—51)

This invention relates to apparatus for lasting and treeing shoes and is disclosed as embodied in a machine of the type shown in the application of W. N. Bray, Serial No. 5,898, filed February 11, 5 1935.

The machine mentioned is for the purpose, among others, of removing wrinkles from the upper materials of lasted shoes. The lasting operation, even when carefully performed, is liable to 10 leave wrinkles in the upper at various localities, and an object of the invention of Bray was to shrink such wrinkles out of the upper by a blast of hot gas, taking advantage of the then dampened condition of the upper. The Bray apparatus 15 comprises a casing into which gas and air are introduced and burned together under pressure, and a nozzle through which the hot products of combustion, together with additional air, if desired, are blown at a substantial velocity against 20 the wrinkled portion of the shoe upper.

While this machine has been quite effective in shrinking away wrinkles left in the upper by the lasting operation, it has been found that more care than can be reasonably expected of the type of 25 operator obtainable for such work is required in the treatment of especially large or deep wrinkles. The operator has a tendency to attempt to reduce such wrinkles too rapidly, applying the hot blast too vigorously and at too high a temperature, 30 with the result that he may burn the upper leather and spoil the shoe.

It is an important object of the present invention to provide an apparatus by which the advantages of the method of treatment provided by 35 Bray may be retained while providing additional means effective in the treatment of heavy wrinkles. To this end we have provided a hot ironing tool, for the treatment of such cases, 40 mounted upon the nozzle of a hot gas blast apparatus.

An important feature of the invention resides in the mounting of the hot ironing tool. We have, in the illustrated embodiment of the invention, so mounted the ironing tool on the hot gas blast apparatus that it is movable, by a movement of the operator's fingers, from an inoperative to an operative position, so that the operator can bring it into use or discard it with a minimum of trouble. It is thrown into a convenient operative position by a trigger, against the tension of a suitable spring, and, on release of the trigger, automatically moves back into inoperative position.

Conveniently the ironing tool of the present invention is heated by the waste heat engendered 55 in the hot gas blast apparatus. To this end the

mounting is such that when in inoperative position the tool rests against the nozzle through which the hot gas blast is rushing, and is thus heated by conduction, the nozzle being at a high temperature due to the presence of the hot gases 5 passing through the nozzle. Also, we have located the operative position of the hot ironing tool directly in the stream of hot gas issuing from the nozzle so that when moved to this position the temperature of the tool is maintained, or perhaps 10 even raised, by the hot blast, while the blast is thereby diverted from the shoe.

Advantageously, we have provided a hinged mounting for the hot ironing tool so designed that when the tool is swung to operative position, and 15 applied to the work, the operative pressure applied to the work through it by the operator is not transmitted back to the operator's fingers, but is resisted by the main body of the apparatus. Thus 20 considerable strain and weariness to the operator are avoided.

These and other features of the invention comprising certain combinations and arrangements of parts will be apparent from the following description of a preferred embodiment of the invention shown in the drawing, in which

Fig. 1 is a side elevation;

Fig. 2 is a plan;

Fig. 3 is a section on the line III—III of Fig. 1; and

30

Fig. 4 is a front elevation.

The hot air generating apparatus may conveniently be of the form shown in the Bray application already mentioned, and is not shown in detail herein. It comprises a hand grip 10 provided 35 with nipples 12, 14 for the supply of air and gas respectively, the gas nipple 14 communicating with a pipe 16 for conveying the gas to a valve 11 at the rear end of a casing 18 in which the gas is burned and its products of combustion are mixed 40 with air in any desired proportions as they pass out to regulate the temperature of the resulting mixture. This resulting hot mixture of gases is delivered through a nozzle 20 in a blast which may be 45 directed upon the work by suitable manipulation of the hand grip 10. For further information reference may be made to the Bray application above mentioned.

A supporting clip 22 is clamped around the front end of the nozzle 20 and has two links 24 50 pivoted to it at 26 under ears 27 at the sides of the nozzle 20. The other ends of the links 24 are pivoted at 28 to the rear side portion of the ironing tool 30. The tool 30 has substantially the outline of an ordinary flat iron, as is seen 55

in Fig. 2, though it is much smaller, and has a smooth rounded bottom 32 (Figs. 1 and 4). Its rear face is cupped, as shown in Figs. 1 and 3, so that it is thin enough to conduct heat rapidly. 5 It has a pair of obliquely, backwardly and upwardly extending arms 34 pivoted at 36 to the upper ends of a forked lever 38, which is pivoted at 40 in notches in the forked front end of a bracket 42 fastened to the hand grip 10. The 10 lower end of the lever 38 is extended below the pivots 40 into a finger grip 44. A spring 46 connects the lever 38 to an abutment 48 on the bracket 42, and holds the lever 38 and iron 30 in the full line inoperative position shown in Fig. 15 1, with a face 50 on the rear side of the iron in contact with the nozzle 20.

The ironing tool in this position is kept hot by heat radiated from the nozzle 20, and conducted through the nozzle and the face 50. When 20 it is desired to put the iron into use the operator pulls on the extension 44 with his forefinger, which moves the lever 38, link 24, and iron 30 into the dotted line positions in Fig. 1, with the links 24 resting against the bosses 52 of the ears 25 27. This brings the ironing tool 30 directly in front of the nozzle where the hot air blast will maintain and perhaps increase its temperature, and will be diverted from the shoe. When the operator has finished using the ironing tool he 30 will release the extension 44, and the spring 46 will snap the tool back into the inoperative full line position of Fig. 1.

In practice the operator will use the apparatus as described in the Bray application referred to, 35 shrinking out the wrinkles in the upper by applying the hot air blast to the wrinkled portions. In case a wrinkle is encountered which is too pronounced to yield readily to the hot air blast alone, he will throw the ironing tool 30 into operative 40 position and rub such a wrinkle down with it.

Having described our invention, what we claim as new and desire to secure by Letters Patent of the United States is:

45 1. An apparatus for use in operating on shoes comprising a tubular member adapted to conduct a stream of hot gas and to direct it upon a shoe, and an ironing tool mounted thereon and having an inoperative position substantially in contact with the tubular member and an operative 50 position remote from the tubular member and directly in the path of the stream of hot gas, whereby the tool is heated by conduction through the tubular member when in inoperative

position and is heated directly by the stream of hot gas when in operative position.

2. An apparatus for use in operating on shoes comprising a tubular member adapted to conduct a stream of hot gas and to direct it upon a shoe, 5 an ironing tool mounted thereon and having an inoperative position substantially in contact with the tubular member and an operative position remote from the tubular member and directly in the path of the stream of hot gas, and a manually operable member for moving the ironing tool from inoperative to operative position.

3. An apparatus for use in operating on shoes comprising a tubular member adapted to conduct a stream of hot gas and to direct it upon a shoe, 15 an ironing tool mounted thereon and having an inoperative position substantially in contact with the tubular member and an operative position remote from the tubular member and directly in the path of the stream of hot gas, and a manually operable member for moving the ironing tool from inoperative to operative position, 20 said ironing tool being resiliently held in inoperative position.

4. An apparatus for use in operating on shoes 25 comprising a tubular member adapted to conduct a stream of hot gas and to direct it upon a shoe, and an ironing tool mounted thereon and having an inoperative position substantially in contact with the tubular member and an operative 30 position remote from the tubular member and directly in the path of the stream of hot gas, whereby the tool is heated by radiation from the tubular member when in inoperative position and is heated directly by the stream of hot gas when 35 in operative position and whereby the stream of hot gas is diverted from the shoe when the ironing tool is in operative position.

5. An apparatus for use in operating on shoes comprising a tubular member adapted to conduct a stream of hot gas and to direct it upon a shoe, 40 and an ironing tool pivotally mounted thereon and having an inoperative position remote from the part of the hot gas blast and swingable on its pivotal mounting to an operative 45 position directly in the path of the hot gas blast, said pivotal mounting providing an abutment constructed and arranged to take the pressure transmitted from a shoe through the ironing tool when the tool is in operative position and 50 is applied to a shoe.
